WILLIAM PATTEN AND JAMES PATTEN, OF NEW YORK, N. Y.

PHONOGRAPH SYSTEM.

No. 854,525.

Specification of Letters Patent.

Patented May 21, 1907.

Application filed March 31, 1905. Renewed March 7, 1907. Serial No. 361,146.

To all whom it may concern:

Be it known that we, WILLIAM PATTEN and JAMES PATTEN, both citizens of the United States, and residents of the city of New York, (borough of Manhattan,) in the county of New York and State of New York, have invented a new and Improved Phonograph System, of which the following is a full, clear, and exact description.

Our invention relates to a novel system or plant by means of which articulate speech, music and other sounds may be transmitted from the usual phonograph or other talking machine record over an electrical circuit to a telephone reproducer which may be at any point distant from the phonograph or talking machine.

Our invention involves a novel means by which the person at the receiving end of the system may communicate with the operator at the talking machine end.

It also involves a coin controlled device for controlling this communication.

It further involves means for automatically making and breaking the talking circuit.

It also involves means for automatically throwing the coin controlled device out of action after the service for which the coin was paid has been rendered.

The invention finally involves various other features of major or minor importance, all of which will be set forth hereinafter and particularly pointed out in the claims.

In the practical use of our invention a number of talking machines and a number of telephone receivers are used together for reasons which will be hereinafter fully set forth, but for facilitating illustration we have in the accompanying drawings illustrated only one talking machine and one receiver with its appurtenant parts. Said drawings show the preferred manner of arranging the system.

Figure 1 represents a diagram showing the various circuits and the apparatus connected therewith; and Fig. 2 is a detail view showing the automatic contacts for the conducting and coin controlled device circuits.

Referring to Fig. 1, 10 indicates an annunciator which may be of any desired form. In connection with the annunciator a circuit making device 11 is employed, which device also may be of any form desired. As here shown the annunciator has ten drops, and it is connected with the circuit making de-

vice 11 by means of ten circuits composed of a main conductor 12 and ten return conductors 14, any one of which may be connected with the main conductor 12 by means of the circuit making device 11, as will be understood. The annunciator circuits are normally open, both by reason of the normally open circuit making device 11 and also by reason of the legs 12^a of the main circuit 12 being provided with separate contacts 15. These contacts are entered into the chute 16 of a coin controlled apparatus.

17 indicates a stop which is normally entered into the chute so as to arrest the movement of the coin through the chute when said coin engages the contacts 15. Therefore, when a coin is inserted into the chute the contacts 15 are connected and upon the operation of the circuit making device 11 the annunciator 10 may be operated.

The stop 17 is connected to a swinging arm 18, and this in turn is engaged by a spring 19 which yieldingly holds the stop in position.

20 indicates an electro-magnet for retracting the stop 17, and this magnet is intended to be energized from one of the legs 12^a of the main conductor 12 by means of a conductor 21 passing to the magnet or a conductor 22 which is returned to the main conductor 12 by devices which will be described hereinafter.

23 indicates the horn or mandrel of the phonograph or other talking machine, and 24 the carriage which moves along the mandrel, holding the stylus 25 of the reproducer device 26 in position on the record of the phonograph. The parts 23 and 24 are of the usual or any desired construction, and 25 the carriage 24 is provided with any desired means for automatically lifting the reproducer out of engagement with the record when the reproducer reaches the end of the record and automatically returning the carriage to the starting point. These means are indicated in outline at 27 in Fig. 1.

Mounted on the base of the phonograph by means of an arm 28 or any other desired device, is a contact arm 29 which is insulated from the supporting arm as shown. This contact is in connection with the conductor 22, and coacting with the contact is a spring finger 30 mounted on or insulated from the carriage 24 of the phonograph. Said spring finger 30 is connected by a conductor 31 with the main conductor 12 of the annuncia-

tor circuit. When, therefore, the parts 29 and 30 are in contact the current will flow from the battery with which the main conductor 12 is connected to one of the legs 12^a of said conductor, thence by the conductor 21 to the magnet 20, and from the magnet 20 by the conductor 22 to the conductor 29, and across by the finger 30 to the conductor 31 and back by said conductor to the main conductor 12.

The reproducer 26 may be of any desired sort. It is preferably, however, one which offers a resistance to the passage of the electrical current and which varies this resistance so as to produce the electrical undulations corresponding to the sound waves impressed on the record of the phonograph. Said reproducer 26 is included in the talking circuit, which comprises conductors 32 and 33 passing from the reproducer. The former conductor is in connection with a spring finger 34 carried by or insulated from the carriage 24, and when the reproducer is in active position said finger 34 runs along the under side of a conductor bar 35 which, as best shown in Fig. 2, is sustained by insulated supports 36 rising from the base of the phonograph. A conductor 37 passes from the contact bar 35, and this conductor, with the conductor 33, is in connection with a telephone receiver 38 which may be of any form desired. When the reproducer 26 is moved down into engagement with the record of the phonograph and the operation of the phonograph begun, the finger 34 will be moved up into contact with the bar 35 as shown, and the finger 30 will be raised to a position which will enable it to contact with the part 29 when said finger reaches a position opposite the part, as shown in Fig. 2. When the reproducer 26 is thrown up out of engagement with the record of the phonograph, the finger 34 is dropped down out of engagement with the conductor bar 35, and simultaneously the finger 30 is moved down to a plane below that of the contact 29, thus enabling the carriage of the phonograph, with the parts 30 and 34, to be returned unobstructedly to the starting position.

The operation of the system as a whole is as follows: A person, whom for convenience we shall term a customer, desiring to hear the phonograph or talking machine, will insert a proper coin in the chute 16. This coin will be arrested by the normally active stop 17, and said coin will then electrically connect the legs 12^a of the main conductor 12. The annunciator circuits are now closed excepting for the circuit maker 11. The customer now presses down one or more of the ten buttons on the circuit maker 11, closing one or more of the annunciator circuits and dropping certain numbers on the annunciator. The operator in charge at the phonograph end of the system is thus in-

formed by the annunciator what particular record the customer desires to hear. The operator then places the desired record on the phonograph or talking machine, and presses the reproducer 26 down into position starting the operation of the machine. The finger 34 engages the bar 35 and closes the talking circuit, so that the customer with the telephone receiver 38 at his ear may hear at any distance the subject impressed on the phonograph record. The carriage 24 runs along during the operation of the phonograph, and when the finger 30 reaches the contact 29 it rides over said contact, thus closing the coin controlled apparatus circuit 80 so that the energized magnet 20 retracts the stop 17 and permits the coin to drop from the chute. This throws open the annunciator circuit and prevents the customer from further operating the annunciator. A short time after when the phonograph carriage reaches the end of its movement it is automatically thrown up by the device 27 and returned to its starting position, this action resulting instantly in breaking the talking circuit. The customer is, therefore, served and the coin which was used to close the annunciator circuit may be collected in a box or receptacle provided therefor. If the customer desires a second operation this may be brought about by inserting a second coin in the chute and repeating the movement described.

One manner of practically employing the invention is in a place of entertainment where a number of receivers 38 with their appurtenant circuit makers 11 and coin controlled apparatus 16 will be provided. All of this apparatus will be placed in a room or rooms convenient for the purpose, and will be in circuit after the manner above described, with one or more annunciators and phonographs. A single operator will be placed in charge of the phonographs, and guided by the annunciators will be able to serve a number of customers simultaneously. It will be observed that the operator has only to insert the record into the machine and start the operation of the machine, the other operations being carried out automatically. We have not illustrated the device for lifting the reproducer 26 from the record and returning the same, for the reason that these are not new with our invention and are commonly known in the art.

Having thus described the preferred form of our invention, what we claim as new and desire to secure by Letters Patent is:—

1. A talking machine system comprising the combination of a talking machine including a reproducer capable of creating electrical undulations corresponding to the subject impressed on the record of the talking machine, a talking circuit including a receiver removed from the talking machine, means

for signaling from the receiver to the talking machine, a coin controlled device controlling said signaling means, and devices actuated by the talking machine automatically resetting said coin controlled device.

2. A talking machine system comprising the combination of a talking machine including a reproducer capable of creating electrical undulations corresponding to the subject impressed on the record of the talking machine, a talking circuit including a receiver removed from the machine, a means for signaling from the receiver to the talking machine, a coin controlled device controlling said signaling means, and an electrical means including contacts automatically engaged upon the operation of the talking machine for resetting the coin controlled device.

3. In a talking machine system, the combination of a talking machine including a reproducer capable of creating electrical undulations corresponding to the subject impressed on the record of the talking machine, a talking circuit including a receiver removed from the talking machine, an electrical means for signaling from the receiver to the talking machine, said signaling means including an open circuit, a coin controlled device comprising a chute and stop adapted to hold the coin into a position to close said circuit of said signaling means, and devices operated upon the operation of the talking machine for retracting the stop from the coin chute to release the coin.

4. In a talking machine system, the combination of a talking machine including a reproducer capable of creating electrical undulations corresponding to the subject im-

pressed upon the record of the talking machine, a talking circuit including a receiver removed from the machine, an electrical means for signaling from the receiver to the talking machine, said means including an open circuit, a coin controlled device comprising a chute and stop adapted to hold the coin in position to close said circuit of said signaling means, an electro-magnet adapted to retract the stop, and means including a contact moving with the carriage of the talking machine, and also including a second contact stationary with respect to the first contact whereby upon the operation of the machine automatically to energize said magnet.

5. In a talking machine system, the combination of a talking machine, including a reproducer capable of creating electrical undulations corresponding to the impression on the record of the talking machine, the talking circuit including a receiver removed from the talking machine, an electrical signal juxtaposed to the talking machine, means for operating the signal juxtaposed to the receiver, a coin controlled device commanding the circuit of the signal to open or close the same, and means for automatically resetting said coin controlled device, said means being operated by the talking machine.

In testimony whereof we have signed our names to this specification in the presence of two subscribing witnesses.
